LIQUID DISPENSING DEVICE

Arthur N. Milster, St. Louis, and Ralph W. Shartle, Richmond Heights, Mo., assignors to Wagner Electric Corporation, St. Louis, Mo., a corporation of Delaware

Application June 9, 1950, Serial No. 10,446

Term of patent 14 years

(Cl. D52—1)

To all whom it may concern:

Be it known that we, Arthur N. Milster and Ralph W. Shartle, citizens of the United States, and residents of St. Louis, Missouri, and Richmond Heights, Missouri, respectively, have invented a new, original, and ornamental Design for a Liquid Dispensing Device, of which the following is a specification, reference being had to the accompanying drawing, forming part hereof.

Fig. 1 is a plan view of a liquid dispensing device, showing our new design.

Fig. 2 is an elevational view of the front of the device; and

Fig. 3 is an elevational view of the rear of the device.

The dotted line showing in the drawing is for illustrative purposes only.

We claim:

The ornamental design for a liquid dispensing device, substantially as shown and described.

ARTHUR N. MILSTER.
RALPH W. SHARTLE.
